CLAIM

The ornamental design for an elastic support cuff for an article of clothing with elastic attachment bridge as shown and described.

DESCRIPTION

FIG. 1 is a perspective view of an elastic support cuff for an article of clothing with elastic attachment bridge in a first state in a first configuration;

FIG. 2 is an elevation view thereof;

FIG. 3 is a perspective view of an elastic support cuff for an article of clothing with elastic attachment bridge in a first state in a second configuration;

FIG. 4 is an elevation view thereof;

FIG. 5 is a perspective view of an elastic support cuff for an article of clothing with elastic attachment bridge in a second state in a first configuration;

FIG. 6 is an elevation view thereof;

FIG. 7 is a perspective view of an elastic support cuff for an article of clothing with elastic attachment bridge in a second state in a second configuration;

FIG. 8 is an elevation view thereof;

FIG. 9 is a perspective view of an elastic support cuff for an article of clothing with elastic attachment bridge in a third state in a first configuration;

FIG. 10 is an elevation view thereof;

FIG. 11 is a perspective view of an elastic support cuff for an article of clothing with elastic attachment bridge in a third state in a second configuration; and,

FIG. 12 is an elevation view thereof.

The dash-dash broken lines show environment and form no part of the claimed design. The dash-dot broken lines show boundaries of the claim and form no part of the claimed design. The back of the elastic support cuff for an article of clothing with elastic attachment bridge forms no part of the claimed design. The interior of the article of clothing forms not part of the claimed design.
